UNITED STATES PATENT OFFICE.

ANTON ARLT, OF BAD SOMMERSTEIN, GERMANY.

VAGINAL SYRINGE.

SPECIFICATION forming part of Letters Patent No. 655,540, dated August 7, 1900.

Application filed September 22, 1899. Serial No. 731,294. (No model.)

To all whom it may concern:

Be it known that I, ANTON ARLT, a subject of the Emperor of Austria-Hungary, residing at Bad Sommerstein, near Saalfeld, Germany, 5 have invented certain new and useful Improvements in Vagina-Pipes; and I do hereby declare the following to be a full, clear, and exact description of the invention, such as will enable others skilled in the art to which 10 it appertains to make and use the same.

My invention relates to vaginal-syringe nozzles, and comprises an improved arrangement which, as compared with other well-known devices of the same class, possesses 15 the advantages of being easily handled and enabling the vagina to be completely closed by means of a taper or funnel shaped plug, so that the irrigating liquid may be kept therein for any desired length of time. A further 20 important advantage is gained by the peculiar form of the syringe, whereby injury to the womb is entirely precluded. This device, with or without a rose-head, is exceedingly convenient in use.

25 A vaginal syringe made according to my said invention is represented in the accompanying drawings, wherein—

Figure 1 shows an elevation, Fig. 2 a longitudinal section, and Fig. 3 a transverse section, of the same.

30 This vaginal syringe possesses a taper or funnel shaped plug *a*, preferably consisting of hard rubber, and which, as shown in Figs. 2 and 3, may be made hollow. In the center 35 of this taper or funnel shaped plug *a* I pro-

vide the tubular member *b*, serving for the passage of the irrigating liquid and made in one piece with the plug, the said pipe terminating above in a cap *c* and below in a rose-head *d*. This syringe may be employed either 40 with or without the rose-head, which latter serves for weakening the jet and enables the liquid to irrigate all parts of the vagina.

For facilitating the closing of the vagina through the medium of the funnel-shaped 45 plug this plug is furnished with a nose or bulge *e*.

Having now particularly described and ascertained the nature of my said invention and in what manner the same is to be performed, 50 I declare that what I claim is—

A two-piece vaginal-syringe nozzle comprising a central tubular member or conduit *b* having a valved member at its outer end and having its walls extended and tapered to 55 form a hollow truncated base *a*, said base having one of its faces slightly thickened and having its lower portion extended below the mouth of the tube *b* to form a socket; and a removable apertured member *d* adapted to 60 be received in said socket, and conforming to the contour of the member *a*, substantially as shown and described.

In testimony whereof I affix my signature in presence of two witnesses.

ANTON ARLT.
